UNITED STATES PATENT OFFICE

JOHN WILLIAM HORNSEY, OF SUMMIT, NEW JERSEY, ASSIGNOR TO GRANULAR IRON COMPANY, A CORPORATION OF MICHIGAN

CONVEYER

Original application filed September 8, 1926, Serial No. 134,287. Divided and this application filed March 18, 1929. Serial No. 348,066.

In a co-pending application, Serial No. 134,287 filed September 8, 1926, I have described apparatus used in the direct reduction of oxides of metals and have shown 5 therein a specially constructed conveyer adapted for transferring a hot charge from one point to another.

The present application is a division of the above application and is directed chiefly 10 to the improved structural features of the special conveyer.

The invention will be fully apparent from the following specification when read in connection with the accompanying drawings, in 15 which:

Fig. 1 is a view of a portion of an apparatus used in the direct reduction of metals with my improved conveyer embodied therein.

20 Fig. 2 is a transverse section on line 2—2 of Fig. 1.

Fig. 3 is an enlarged cross sectional view of the conveyer taken on line 3—3 of Fig. 1.

Fig. 4 is an enlarged longitudinal section 25 on line 4—4 of Fig. 2.

Referring in detail to the drawings, 1 is a rotary drum adapted to receive a charge of ore to be preheated therein. This drum projects into the open end 16 of a stationary 30 structure 26. An annular, flexible seal 17 is interposed between the fixed structure 26 and the rotating cylinder 1 so as to prevent the escape of dust.

A reducing cylinder 24 is operatively associated with the right end of the stationary 35 structure 26 and a suitable seal 34 is provided between the two to prevent the escape of dust and gases.

The preheated ore coming from the rotary 40 cylinder 1 falls into a transverse chamber 20 formed in the stationary structure and onto a grating 22 located above the inlet of an ore conveyer 23. Alongside of the ore conveyer 23 is a coal conveyer 28. The ore conveyer 45 is of special construction. It is important in apparatus of this character to feed the ore, which is preheated in the cylinder 1, in a hot state to the cylinder 24. This would ordinarily weaken the conveyer 50 structure. I propose to strengthen it in

the manner illustrated in the drawings. The conveyer is housed within the shell 29 embedded in the brick work of the stationary structure 26. Within this shell 30 there is a metal tube 31 having at spaced intervals a plurality of supporting lugs 31^a, providing segmental spaces through which water is circulated so as to maintain the parts at a desirable temperature in order to prevent warping or otherwise distorting the parts. Within the tube 31 there is an inner tube 32, preferably made of metal, adapted to resist high temperatures. This inner tube is formed with a number of lugs 32^a serving to hold the same in spaced relationship to the inner wall of the intermediate tube 31. This provides air spaces. If desired, suitable heat insulating material may be used in the annular dead zone between the innermost shell and the intermediate shell. The conveyer screw 23^a is preferably of the screw type and is made of metal especially adapted to resist high temperatures.

The conveyer structure described is particularly advantageous for use in locations where high temperatures are encountered. Where materials such as coal and ore are used in the presence of heat, sintering sometimes takes place which tends to block or choke the conveyer. It is, therefore, advantageous to employ a construction which will permit withdrawal of the conveyer for replacement or repair. The construction described permits of such withdrawal, it being apparent that if, for any reason, the material becomes packed or wedged sufficiently to interfere with the proper operation of the conveyer screw, the entire conveyer structure can be withdrawn as a unit by pulling the shell 30 out of the shell 29 which is embedded in the brick work. The cooling water, or other medium, circulating between the tubes 30 and 31 permits the maintenance of a temperature which will prevent expansion to such an extent that the parts will bind and thus interfere with such withdrawal. For maintaining the circulation of water in the space between the tubes 30 and 31, inlet and outlet pipes *p*, *p'* are provided.

While I have described quite specifically 100

the construction of the conveyer illustrated, it is not to be construed that I am limited thereto, since various modifications may be made by those skilled in the art without departing from the invention as defined in the appended claims.

5 What I claim is:

1. A conveyer for hot material having a central conveyer tube, an intermediate tube separated from the first and having an insulating medium between the two, and a third tube surrounding the intermediate tube with means for passing water between the intermediate tube and the third one.
- 10 2. In an apparatus of the class described, a stationary structure having a shell fixedly embedded therein, a central conveyer tube enclosing a screw conveyer, an intermediate tube separated from said conveyer tube to accommodate an insulating medium, and a third tube surrounding the intermediate tube, and means for passing water between the intermediate tube and the third one.
- 15 3. In an apparatus of the class described comprising a shell embedded in a stationary structure, a central conveyer tube enclosing a conveyer, an intermediate tube separated from the conveyer tube to accommodate an insulating medium, a third tube surrounding the intermediate tube, spacing means between said third tube and said intermediate tube, and means for passing water between the intermediate tube and the third tube.
- 20 4. In an apparatus of the class described, a metal shell incorporated as an integral part of a masonry structure, and a water cooled conveyer loosely engaging said shell so as to be removable as a unit therefrom.
- 25 5. In an apparatus of the class described, a metal shell embedded in a masonry structure and a conveyer loosely mounted in said shell, said conveyer comprising a central conveyer tube, an intermediate tube separated from the first to accommodate an insulating medium, and a third tube surrounding the intermediate tube with means for passing water between the intermediate tube and the third one.

40 In witness whereof I have hereunto signed
50 my name.

JOHN WILLIAM HORNSEY.
